UNITED STATES PATENT OFFICE.

JOHN HENBERGER, OF NORTH CHILlicothe, ILLINOIS.

TIE-PLATE.

1,038,578.

Specification of Letters Patent. Patented Sept. 17, 1912.

Application filed September 15, 1911. Serial No. 649,409.

To all whom it may concern:

Be it known that I, JOHN HENBERGER, a citizen of the United States, residing at North Chillicothe, in the county of Peoria 5 and State of Illinois, have invented a new and useful Tie-Plate, of which the following is a specification.

This invention relates to tie plates or bridge plates for railroad joints, and has for its object to provide means for anchoring rail joints to the ties.

This invention is particularly adapted for rail joints wherein the abutting ends of the rails lie between the ties and serves both 15 as a means for supporting the ends of the rails and for anchoring the rail joints or fish plates to the ties, and resides in the novel arrangement and construction of parts as hereinafter described and as illustrated 20 in the accompanying drawings, wherein similar reference characters indicate similar parts, and wherein—

Figure 1 is a perspective view of the tie plate. Fig. 2 is an elevation of the tie plate 25 as in use. Fig. 3 is a transverse section taken through a rail joint with the tie plate applied thereto. Fig. 4 is a similar view showing a modified form of tie plate applied to a rail joint, the fish plates of which 30 extend in under the rail. Fig. 5 is a perspective view of the modified form of tie plate used in the joint shown in Fig. 4.

Referring specifically to the drawings, there are designated at R—R the abutting 35 ends of two rails which are connected by the usual angle iron fish plates F and bolts B, the ties being designated at T between which the abutting ends of the rails R lie.

The tie plate or bridge comprises an elongated metallic plate, 6, which is preferably of wrought iron, and is adapted to seat upon two adjacent ties under the rail joint or is interposed between the rail joint and the underlying ties T. This plate is provided 40 with a pair of longitudinal grooves or channels 7 extending the full length thereof, the rails being adapted to rest upon the plate 6 between the said grooves with the grooves lying below the edges of the base flanges, 45 and at each end the plate is provided with a pair of square spike holes 10 adjacent the outer edges of the grooves 7. At one end the plate 6 is provided with a depending transverse lip 12 and at the other end there- 50 of are a pair of upstanding spaced lugs 11 at the sides of the grooves 7 to snugly re- ceive the base flange of one rail. An up- 55 standing rib or flange 13 extends along one side of the plate and is arranged adjacent the corresponding spike holes 10 and at the 60 sides of the plate intermediate the ends thereof are longitudinal depending flanges 8 having the vertical shoulders 9 at the ends thereof facing the end of the said plate hav- 65 ing the lugs 11, the flange 8 on the side of the plate opposite the rib 13 being struck downwardly to form lips 14 at the ends of the plate to rest upon the ties and the other flange 8 lying in the vertical plane of the 70 said rib 13.

In application, the tie plate 6 is arranged 75 upon the ties to bring the lip 12 and the shoulders 9 of the depending flanges 8 against the respective ties. The rails R rest upon the plate intermediate the grooves 7, 75 one of the rails passing between the lugs 11, and the said lugs are adapted to engage the ends of the fish plates F securing the said rails together and also fitting against the edges of the base flange of the correspond- 80 ing rail. The spikes which are employed to secure the fish plate and the rails to the ties are passed through the holes 10 of the tie plate. Upon the expansion or contraction 85 of the rails R tending to draw the fish plate F toward the end of the tie plate having the lugs 11, the lugs 11 engaging the ends of the fish plates cause the tie plate to remain sta- 90 tionary with the fish plates and therefore anchor the fish plates to the ties, the lip 12 90 and the shoulders 9 engaging the outer and inner faces of the corresponding ties to prevent the tie plate from sliding thereupon. In this manner the creeping of the fish 95 plates or rail joint upon the ties is elimi- 95 nated and the relation between the spikes and the fish plates is maintained to increase the efficiency of the joint. The shoulders 9 of the flanges 8 resting against the tie also tend to brace or support the central por- 100 tion of the tie plate thus forming a substan- 100 tial bridge structure for supporting the abutting ends of the rails intermediate the ties. The rib 13 prevents the plate from buckling or being bent and therefore assists 105 the flanges 8 in supporting the central por- 105 tion of the plate.

In the modified form shown in Figs. 4 and 5 in which the tie plate is applied to a rail joint of which the fish plates F' extend in 110 under the rails, the tie plate is similar to the above described tie plate in every re-

spect but is provided with an additional lug 15 between the lugs 11 and between the slots 7. In this construction the lower portions of the fish plates rest upon the tie 5 plate, the lugs 11 engaging the fish plates at the outer corners and the lug 15 engaging the inner corners of the fish plates beneath the rail.

This tie plate is simple in its construction 10 rendering it inexpensive to manufacture, and is both durable and efficient in its use.

What is claimed as new is:—

1. An elongated tie plate for rail joints adapted to be interposed between the joints 15 and the underlying ties, having a pair of upright lugs at one end to snugly receive the base flange of one rail and engage the ends of the fish plates, and having a pair of longitudinal grooves extending throughout 20 the length thereof to lie below the edges of the base flanges of the rails and having spike holes at each end thereof adjacent the outer edges of the said grooves, longitudinal depending flanges having vertical shoulders 25 facing the end of the plate having the said lugs and adapted to abut against the inner face of one of the ties underlying the rail joint, a depending transverse lip at the other end of the plate adapted to engage the 30 outer face of another underlying tie, and an upright rib along one side of the plate arranged adjacent the corresponding spike holes, the corresponding longitudinal flange lying in the same vertical plane with the 35 said rib.

2. An elongated tie plate for rail joints adapted to be interposed between the joints and the underlying ties, having a pair of upright lugs at one end to snugly receive 40 the base flange of one rail and engage the

ends of the fish plates, and having spike holes at each end thereof, longitudinal depending flanges having vertical shoulders facing the end of the plate having the said lugs and adapted to abut against the inner 45 face of one of the ties underlying the rail joint, a depending transverse lip at the other end of the plate adapted to engage the outer face of another underlying tie, and an upright rib along one side of the plate, the 50 corresponding longitudinal flange lying in the same vertical plane with the said rib.

3. An elongated tie plate for rail joints adapted to be interposed between the joints and the underlying ties, having a pair of upright lugs at one end to snugly receive the base flange of one rail and engage the ends of the fish plates and having spike holes at each end thereof, longitudinal depending flanges having vertical shoulders facing the 60 end of the plate having the said lugs and adapted to abut against the inner face of one of the ties underlying the rail joint, a depending transverse lip at the other end of the plate adapted to engage the outer 65 face of another underlying tie, and an upright rib along one side of the plate, the corresponding longitudinal flange lying in the same vertical plane with the said rib, and the other longitudinal flange being 70 struck outwardly to form lips to rest upon the ties.

In testimony that I claim the foregoing as my own, I have hereto affixed my signature in the presence of two witnesses.

JOHN HENBERGER
